UNITED STATES PATENT OFFICE.

WILLIAM BARENZ, OF CHICAGO, ILLINOIS.

VALVE.

1,151,751.

Specification of Letters Patent. Patented Aug. 31, 1915.

Application filed October 12, 1912. Serial No. 725,360.

To all whom it may concern:

Be it known that I, WILLIAM BARENZ, a citizen of the United States, and a resident of Chicago, in the county of Cook and State of Illinois, have invented certain new and useful Improvements in Valves; and I do hereby declare that the following is a full, clear, and exact description thereof, reference being had to the accompanying drawings, and to the letters of reference marked thereon, which form a part of this specification.

This invention relates to an improvement in valves containing a plurality of parts which have to be set or placed in a certain predetermined combination relation in order to open the valve.

My invention is adapted to be applied to a valve structure placed in a pipe-line conducting a fluid from a source of supply to control the flow therefrom and may be applied to a pipe-line from a gasoline supply tank to control the flow of gasoline to the carburetor of an automobile.

The advantage of my improvement will appear as I proceed with my specification.

In the drawings, Figure 1 is a view representing a side elevation of a valve mechanism embodying my invention. Fig. 2 is a view representing a longitudinal central section through the same. Fig. 3 is a view representing a front end elevation of the valve structure. Fig. 4 is a view representing a transverse section taken in a plane indicated by the line 4—4 of Fig. 2. Fig. 5 is a view similar to Fig. 4 with the parts in a different relation. Fig. 6 is a view similar to Fig. 5 illustrating a modified form of my invention.

Referring now to that embodiment of my invention illustrated in the drawings, 10 indicates a tubular valve casing within which are nested a plurality of tubular valve plugs 11. Said valve plugs are capable of rotation with reference to each other and with reference to the valve casing. The valve casing 10 is open at one end and is closed at its other end by a wall 10^a. Said casing is provided intermediate its ends with laterally opening inlet and outlet ports extending, as shown, respectively, through bosses 10^b, 10^c, which are threaded for connection with the pipe line in which the valve structure is placed. The valve plugs 11 also each have end walls 11^a.

To the open end of the tubular valve cas-

ing is attached a fixed disk 12, the upper face of which is stepped to provide a plurality of vertically spaced circular faces 12^a, 12^b, 12^c, one for each of the valve plugs. Said faces are graduated in a circumferential direction, each face being divided into a like number of equal angular graduations, which are indicated by numerals 12^x, 12^y, 12^z. The said graduations, as shown, are indicated by notches 13 in the peripheral edges of the several faces and the numerals indicating the several graduations are numbered consecutively in a circular direction, there being, as shown, twelve of said notches in each face. Preferably the like numerals of the several faces are not placed in radial alinement, the zero point of one dial face being angularly separated from the zero point of either of the other dial faces, for a purpose presently to be described.

The open end of each valve plug is closed by a disk 15, 16, 17, respectively, and said disks are made integral or rigid with devices which project beyond the valve structure in such manner that the several valve plugs may be independently rotated within the valve casing by means operable from the outside of the valve structure. As shown, the valve disk 15 of the inner valve plug is made rigid with a longitudinally extending centrally disposed rod or stem 15^a, while the valve disks 16 and 17 are made integral with concentric tubular stems or sleeves 16^a and 17^a, respectively, which have rotative bearing the one within the other and upon said rod or stem 15^a and also within a sleeve 12^a made rigid with the disk 12 of the valve casing.

To each of the stems of the valve plugs is secured, respectively, a radial arm 19, 20, 21, carrying at its outer end a detent 19^a, 20^a, 21^a, adapted for engagement in one of the graduation notches of one of the dial faces on the disk 12. As shown, each of said arms is threaded upon its valve stem, and thumb nuts 22, 23, 24, respectively, are likewise threaded upon said valve stems and act as jam nuts to lock said arms in any predetermined angular position on their respective valve stems.

Each valve plug is provided with inlet and outlet ports 25, 26, adapted to be brought simultaneously into alinement with the inlet and outlet ports of the valve casing. It is apparent that by rotating the valve plugs by means of the arms 19, 20 and 21,

the inlet and outlet ports of each valve plug may be simultaneously brought into alignment with the inlet and outlet ports of the casing, as shown in Figs. 2 and 4, in which 5 case a free passage will be afforded through the valve structure. In this position of the valve plugs the several detents on the actuating arms of the valve stems will correspond in position with certain graduations 10 on their respective dial faces and thus, in order to open the valve, it is essential that the one operating it shall know these particular graduations. In other words, he must know the combination of the valve 15 structure in order to operate it, as in all of the positions of the valve operating arms, except those predetermined positions known only to the one having the combination, the several inlet and outlet ports of the valve 20 structure in the casing will not be in alignment and the valve will be closed.

As will be apparent, it is possible to change the combination should it become known to others than those authorized to 25 know it by simply setting the valve on its old combination and then, loosening one or more of the jam nuts on the several valve stems, rearranging the relative positions of the radial arms 19, 20 and 21 on their respective 30 dials, the new positions determining the new combination necessary to be produced in order to open the valve.

In the case of the use of the valve in automobiles it is desirable to provide in the 35 valve plugs a second set of inlet and outlet ports of restricted opening, so that the valve may be partially closed off and yet permit sufficient gas to enter the engine to keep it running. In Fig. 6 I have shown the valve 40 plugs provided with restricted inlet and outlet ports 27, 28, respectively, which may be brought into alignment by means of a different combination than that of the main inlet and outlet ports. Thus, when one leaves the 45 automobile he may set the operating arms of the valve in a position corresponding to the position of the inlet and outlet small valve ports 27, 28, when sufficient gas will be supplied the engine to prevent it from stopping but will not be sufficient to start the 50 engine under load.

The advantage of my improved valve structure will be apparent to those familiar with the art. It is simple in construction 55 and economical to manufacture and assemble.

While in describing my improved valve I have shown but three valve plugs, it is apparent that the structure may be made more 60 complicated and less likely to be tampered

with by adding to the number of valve plugs, thus increasing the difficulty of forming the combination to open the valve.

I claim as my invention:—

1. A valve structure comprising a tubular 65 casing having an integral bottom wall and aligned inlet and outlet ports, an apertured dial member forming the top wall of said casing, said dial member having sets of graduations, a plurality of concentric tubular valve plugs each having an integral bottom wall, rotatively mounted and nested in said casing and in each other, each valve plug being provided with inlet and outlet 70 ports adapted to be brought into alignment with the inlet and outlet port of said valve casing, a valve stem fixed to and closing the top of each valve plug, said stems being nested within each other and arranged to extend through the aperture in said dial, 75 means fixed to each valve stem for rotating its associated valve member independently of the other valve members, and an indicator movable with each tubular valve plug 80 adapted to register with an associated set 85 of graduations on said dial.

2. A valve structure comprising a tubular casing having an integral bottom wall and aligned inlet and outlet ports, an apertured dial member forming the top wall of said casing, said dial member having sets of 90 graduations, a plurality of concentric tubular valve plugs each having an integral bottom wall, rotatively mounted and nested in said valve casing and in each other, each valve 95 plug being provided with inlet and outlet ports adapted to be brought into alignment with the inlet and outlet ports of said valve casing, concentric nested valve stems one for each valve plug having rotative bearing 100 within the aperture in said dial and projecting beyond the same, the inner valve plug stem projecting successively beyond the valve stem of the adjacent valve plug, arms 105 fixed to said valve stem, indicators fixed to said arms and adapted to register with an associated set of graduations on said dial and means for attaching said arms to said 110 valve plugs providing angular adjustment of said indicators with reference to said valve plugs.

In testimony, that I claim the foregoing as my invention I affix my signature in the presence of two witnesses, this 9th day of October A. D. 1912.

WILLIAM BARENZ.
